UNITED STATES PATENT OFFICE.

VALENTINE ZWISSSLER, OF PHILADELPHIA, PENNSYLVANIA, ASSIGNOR TO
SAMUEL J. YARGER, OF PHILADELPHIA, PENNSYLVANIA.

STAPLING-MACHINE.

SPECIFICATION forming part of Letters Patent No. 730,070, dated June 2, 1903.

Application filed June 13, 1902. Serial No. 111,443. (No model.)

To all whom it may concern:

Be it known that I, VALENTINE ZWISSSLER, a citizen of the United States, residing in the city and county of Philadelphia, State of Pennsylvania, have invented a new and useful Improvement in Stapling - Machines, of which the following is a specification.

My invention consists of an improved construction of a stapling - machine wherein means are provided for rendering the stapling devices temporarily inoperative in case the machine becomes clogged, provision being made for providing access to the stapling mechanism, so that the broken or twisted staples can be readily removed.

It also consists of an adjustable gage adapted to coact with the stapling devices.

It further consists of novel details of construction, all as will be hereinafter set forth, and particularly pointed out in the claims.

Figure 1 represents a side elevation, partly in section, of a stapling-machine embodying my invention. Fig. 2 represents a section on line $\alpha\alpha$, Fig. 1. Fig. 3 represents a section on line yy , Fig. 1. Fig. 4 represents a view similar to Fig. 3, but showing the stapling devices in an elevated position. Fig. 5 represents a front elevation of Fig. 1. Fig. 6 represents a sectional view similar to Figs. 3 and 4, but showing the position the locking device assumes, whereby the upward movement of the stapling devices is prevented, according to requirements. Fig. 7 represents in detached position a perspective view of the spring employed.

Similar numerals of reference indicate corresponding parts in the figures.

Referring to the drawings, 1 designates a stapling-machine, the same consisting of a bed or base 2, provided with the ears 3, in which the arm or upper portion 4 of the stapling device is fulcrumed, said arm having a vertical opening in its forward portion in which is mounted the vertically-movable spindle 5, the latter having the head 6, which is adapted to be struck or depressed by the hand of the operator, as is customary.

The spindle 5 has an opening 7 therein, which is engaged by the extremity 8 of the lever 9, which is fulcrumed at 10 in the ears 11, said lever being provided with the eye 12

for the insertion of the finger of the operator, wherefrom it will be seen that as the lever 9 is raised and lowered the spindle 5 and its adjuncts will move in unison therewith. 55

13 designates a flattened face or portion of the spindle 5, to the lower portion of which is secured the spring 14, the latter consisting of the upright curved member 16, which is deflected downwardly at the point 17 to form 60 the limb 18, which is offset rearwardly from the main portion 16 thereof, as seen in Fig. 1, and is bent at the point 19 and deflected upwardly to form the member 20.

It is to be understood that the spring 14 is 65 normally curved or bent at its upper end, as seen in Fig. 3, so that when the spindle 5 is in its lowermost position the uppermost portion of said spring will lie in a plane to the left of the vertical center line of the pin 21, 70 so that as the spindle is raised the said pin will contact with the convex side of the spring, so that the latter will be forced to the left of said pin in the further upward movement of the spindle; but the resiliency of said spring 75 is such as to cause it after the spindle has been raised to a point where the bend 19 of said spring comes above the pin 21 to fly over into the position in which it is seen in Fig. 4, so as to lock the spindle against downward 80 movement, as will be readily understood. Should now the spindle be forced downward and the staples be clogged, the spring will be bent or flexed into the position seen by dotted lines in Fig. 4 and the bend 19 thrown off 85 from its engagement with the pin 21 and the spindle depressed, when the spring will fly over into the position seen in Fig. 6 and the upper terminal 20^X engage beneath the pin 21 and the stapling devices locked, it being 90 understood that the downward movement is prevented by the clogging of the staples and the upward movement by the engagement of the portion 20^X with the under surface of the pin.

21 designates a pin which is mounted in a fixed position near the upper extremity of the spindle 5 and is adapted to coact with the spring 14, as will be hereinafter described.

The staples 22 are inserted in a suitable 100 guide or raceway 23 and are propelled forwardly by means of the feeder 24, as will be

apparent to those skilled in the art; but as the staple supporting and feeding devices form no part of my invention *per se* I deem it unnecessary to describe the same in detail. 5 It will, however, be apparent that as each staple is fed to its extreme forward position it will be directly under the clenching device 25, the latter consisting of a blade attached to the spindle 5 and being adapted to 10 contact with a staple during the act of clenching the same, as will be understood from Fig. 3. In case a staple becomes bent or broken or assumes such a position as to clog the clenching device and thereby render the same 15 temporarily inoperative it is very desirable that means be provided so that access may be had to the staples and clenching mechanism. To effect this, I have provided the outer extremity of the arm 4 with a cap 26, which is 20 hinged at the point 27, the said cap being provided with an ear 28, which is adapted to be secured to the stationary ear 29 by the screw or other fastening devices 30, so that in case the clenching device 25 becomes stuck 25 or inoperative by reason of a broken or improperly-bent staple upon the removal of the screw 30 the cap 26 can be swung into the position seen in Fig. 5 and the parts rendered 30 readily accessible for the purposes of inspection or repairs.

The cap 26 is provided with ways 31, which serve to guide the clenching device 25 in its reciprocations and also as a chamber for the reception of the staple, which has been propelled to its extreme forward position.

In order that the staples may be clenched in a uniform manner, I provide in addition to the clenching device an adjustable gage or table, the same consisting of the laterally-extending portions 32 and the upwardly-extending abutments 33, against which the paper to be stapled is placed, said portions 32 and 33 being carried upon the arm 34, which is prolonged to form the base portion 35, having the 45 slot 36 therein, through which passes the screw 37, whereby the abutment 33 can be moved toward or away from the stapling devices, according to requirements.

In the operation of the machine the arm 4 50 can be readily raised and lowered by the insertion of a finger of the operator in the eye 12, it being apparent that when the arm assumes the position seen in Fig. 1 the eye 12 of the lever 9 may be depressed and the spindle 5 and its adjuncts will assume the position seen in Fig. 4, the portion 19 of the spring 14 moving upwardly from the position seen in Fig. 3 to the position seen in Figs. 4 and 5, and the staple having been propelled forwardly into the recess or chamber 31 and the clenching device 25 having been depressed by a blow upon the head 6 it will be apparent that the staple will be clenched when the parts assume the position seen in Fig. 3.

65 It will be apparent from an inspection of Fig. 3 when the spindle 5, carrying the spring and its adjuncts, is raised from the position

seen in Fig. 3 to the position seen in Fig. 4, the right-hand portion of the member 18 of the spring will ride around the pin 21, so that 70 when the spindle 5 and the stapling devices are in their highest position the portion 19 will be slightly in contact with the pin 21, and a blow on the head 6 will effect the clenching of the staple when the parts assume the 75 position seen in Fig. 3. In case, however, an improper number of staples are presented to the stapling device, or in case the staples become clogged within the cap or staple-case 26, the stapling devices will become locked in 80 the position seen in Fig. 6, wherein the extremity 20^x of the member 20 will be in contact with the pin 21, an upward movement of the spindle and its stapling devices from the position seen in Fig. 6 to the position seen in 85 Fig. 4 will be prevented, a downward movement of the stapling device being prevented by the clogging of the staples within the cap 26. The operator then by opening the cap 26 into the position seen in Fig. 5 can ascertain 90 the cause of the trouble and remedy the same, whereupon by depressing the parts from the position seen in Fig. 6 to the position seen in Fig. 3 the stapling devices can be readily elevated, as indicated in Fig. 4. 95 In other words, it is necessary for the spindle 5 and its adjuncts to make a complete upward and downward stroke in order to properly permit the feeding and clenching of the staples.

100 It will be apparent that the contour of the spring 14 can be slightly changed according to requirements, and that other equivalent devices therefor may be employed without departing from the spirit of my invention, 105 which consists, broadly, in providing stapling devices with a temporary locking device, as above explained, whereby the operator is enabled to ascertain and remove the cause of the trouble should any exist.

110 By loosening the screw 37 and moving the arm 34, carrying the abutments 33, toward or away from the clenching device the device can be adjusted so that the staples will appear in uniform relative positions. In case 115 the stapling device becomes stuck or clogged the parts are readily accessible for the purpose of inspection and repairs upon loosening of the screw 30, whereupon the cap 26 can be swung into the position seen in Fig. 5, as 120 has been explained.

125 It will be apparent that various changes may be made by those skilled in the art, which will come within the scope of my invention, and I do not, therefore, desire to be limited in every instance to the exact construction herein shown and described.

130 Having thus described my invention, what I claim as new, and desire to secure by Letters Patent, is—

1. In a stapling-machine, an arm pivotally supported, a spindle movable in said arm, a pin secured in fixed position in said arm, and a spring normally curved and having a bend

intermediate its ends and a bend at its upper end, and a spring member with a stop-shoulder intermediate said bends, said spring being carried upon said spindle and adapted to 5 coact with said pin, whereby said spindle is prevented from upward movement during its ascent whenever clogging of the staple occurs and also locked in its downward movement.

2. In a stapling-machine, an arm pivotally supported, a spindle vertically movable in said arm, and having a flattened portion, a normally curved spring secured upon said spindle in proximity to said flattened portion, 15 said spring consisting of the member 16 deflected downwardly at the point 17 to form the member 18, the latter being bent upon itself intermediate the ends of the spring and deflected upwardly at the point 19 to form

the member 20, a pin secured in fixed position and adapted to coact with said spring and a clenching device carried by said spindle. 20

3. In a stapling-machine, an arm pivotally supported, a spindle vertically movable in said arm, a normally curved spring secured 25 upon said spindle, said spring consisting of the member 16 deflected downwardly at the point 17 to form the member 18, the latter being deflected upwardly at the point 19 to form the member 20, in alignment with the member 18, a pin secured in fixed position and adapted to coact with said spring and a clenching device carried by said spindle. 30
